[57] CLAIM

The ornamental design for a lipstick case or similar article, substantially as shown and described.

DESCRIPTION

FIG. 1 is a perspective view of a lipstick case or similar article showing my new design;

FIG. 2 is a top plan view thereof;

FIG. 3 is a side elevational view thereof;

FIG. 4 is a side elevational view similar to FIG. 3, but of the opposite side;

FIG. 5 is a bottom plan view thereof; and

FIG. 6 is an exploded perspective view thereof with the cap removed for convenience of illustration.
